SAUCER FOR A TEA BAG OR THE LIKE

David M. Shatan, Mamaroneck, N.Y., assignor to Presto
Plastics Corporation, Mamaroneck, N.Y.

Filed Oct. 9, 1970, Ser. No. 55,419

Term of patent 14 years

Int. Cl. D7—06

U.S. Cl. D44—9

FIG. 1.

FIG. 2.

FIG. 3.

FIG. 4.

FIG. 1 is a perspective view of a saucer for a tea bag or the like showing my new design;

FIG. 2 is a reduced scale top plan view;

FIG. 3 is a right side elevational view; and

FIG. 4 is a front edge elevational view.

I claim:

The ornamental design for a saucer for a tea bag or the like, substantially as shown.
